UNITED STATES PATENT OFFICE

FREDERICK B. ADAM, OF ST. LOUIS, MISSOURI, ASSIGNOR TO FRANK ADAM ELECTRIC CO., OF ST. LOUIS, MISSOURI, A CORPORATION OF MISSOURI

PANEL CABINET

Application filed April 28, 1930. Serial No. 448,058.

This invention relates to panel cabinets, and more particularly to an improved cabinet which embodies a construction designed to overcome certain difficulties encountered 5 in the installation of flush-type dead-front panel equipment as will hereinafter be explained.

In the installation of electrical outlets, fuse boxes, and panelboards, it is the usual 10 practice to install the boxes at the same time that the conduit and wiring is installed, that is, before the plastering of the wall has been accomplished. After the walls have been 15 finished, it is sometimes found that the box is positioned at a depth in the wall so that the front edges do not lie flush with the wall surface. This results in a space being left 20 between the panelboard and the cabinet front which, if the space is great enough, may permit personal exposure to the wiring, and in any event mars the appearance of the installation.

In certain panelboards of heretofore known type, an attempt has been made to 25 remedy this condition by a construction which permits adjustment between the panelboard and wall box, but in which the adjustment must be accomplished before the front or trim has been mounted. Thus, the panelboard is adjusted and secured in the wall 30 box at a distance estimated to be suitable for engagement with the front or trim when that member is afterwards mounted. If the panel has been incorrectly positioned, the 35 front must again be removed and the panel readjusted, until, by trial and error, an approximate mating of the parts is effected.

It is therefore an object of this invention to provide a panelboard in which the panel 40 member may be positively adjusted in the first instance, by a single, simple operation, to suit conditions of the particular installation after the front has been mounted.

Another object is to provide, in connection 45 with a panelboard, a front or trim which has a depressed portion or return, adapted to serve as a guard member, and which engages a portion of the panel member.

A further object of this invention is to 50 provide a construction in which the recited

guard member is secured to the front as a unit, thereby enabling the ready removal and replacement of the front and guard member for access to the wiring and connections.

These and other objects will appear from 55 the following detailed description and accompanying drawing in which Fig. 1 is a plan view of a fuse block adapted for use in a wall box which is shown in perspective in Fig. 2; Fig. 3 is a perspective view of a 60 unitary structure including a front, a return and a framing-plate for the fuse panel, and Fig. 4 is a vertical section showing the parts in assembled relation.

Referring now by reference numerals to 65 the drawing, the fuse block illustrated in Figs. 1 and 4 comprises, preferably, a base 5 of insulating material having a raised portion 6 in which fuse sockets 7 are disposed and arranged in any suitable formation. 70 The portion 6 by preference is rabbeted to provide a small marginal shoulder 8 which outlines the normally visible portion of the fuse block. Each fuse socket is provided with the customary screw shell which engages 75 a branch terminal member or contact post 9. In the present embodiment, the members 9 extend laterally from their respective sockets, and are seated in depressions 10 in the base. The bottom of the base 80 is recessed to accommodate busses in the form of straps 11, each of which forms a common conductor for a group of fuses, the central terminal of the fuse receptacles in each group being connected to one of the straps. Each 85 strap terminates at one end of the block in a connector lug 12 seated in a depression 13 in the fuse block. At the opposite end and also depressed in the block is a terminal bar 14 having a plurality of binding posts 16 90 and a terminal lug 17. As is understood by those familiar with the art, the terminal bar 14 adapts the device to various circuit arrangements for both two and three wire systems.

While the above description deals 95 with a fuse block, the scope of the invention is in no way restricted to that particular form of panel. The construction herein set forth readily lends itself to panelboards of any practical size.

The box illustrated in Fig. 2 is formed of sheet material provided with knockouts, and in size the box is substantially larger than the panel which it is adapted to accommodate, thereby providing ample room for wiring and connections. The box has means for securement of a cover plate, hereinafter described, such means being shown in the form of lugs 15, projecting inwardly, one adjacent each corner. The lugs 15, in the present construction, are formed from portions of the wall material and each is provided with a threaded aperture for engagement with a cover holding screw 18. The box is provided with apertures for the passage of screws or similar fastening means to secure the box in a wall.

To support the panel, I provide, by preference, a plurality of studs 20, fixedly secured to the box bottom as by riveting, having their free ends slightly tapered for a purpose hereinafter appearing. The panel block is provided with apertures 21, relatively disposed to correspond with the relative positions of the studs with which they are in register and adapted to accommodate. The number of studs and apertures provided is not of particular importance, since any one of the studs is sufficient to support the weight of the panel.

The cabinet front, illustrated in perspective in Fig. 3, comprises essentially, a flat rectangular front or plate having, in the present embodiment, a centrally located door opening. A door 22, hingedly mounted on the front is provided with a knob or handle (not shown) and a latch or staying device 23. Openings 24 are so disposed in the front that when the latter is placed over the box they will be in register with the threaded apertures in the lugs 15. The cover holding screws 18, already mentioned, are by preference of sufficient length to permit, if necessary, the cover plate to be mounted at a substantial distance away from the edges of the box. This condition arises when the box is set at such a depth that the fastening lugs 15 are remote from the surface of the wall.

For the purpose of providing a completely closed and entirely shielded structure, and one in which only the face portion of the panelboard is visible when the cabinet door is in open position, I provide a return 19 with which is combined a framing-plate 25. In the present example the members 19 and 25 are formed of sheet material and together resemble a shallow pan. Obviously, the return and plate structure may be an integral part of the cabinet front, but I prefer to form it separately, and provide flange portions 26 by which I weld, or otherwise suitably attach, the return to the front. The inner portion of the plate member 25 is provided with an opening which conforms with the raised portion of the fuse block, and the

margins of which oppose the shoulder 8. The fuse block and framing plate are fastened together by means of screws 27 which pass through apertures 28, in the framing plate, and engage nuts (not shown) which are by preference embedded in the block and provide seats 29 for the screws 27.

From the foregoing it is obvious that, when the box is mounted in a wall, with the wiring brought thereto, the panelboard is inserted so that the apertures 21 receive the studs 20, after which wiring connections are made. The unitary assembly, comprising the front, return and framing plate, may then be applied, with the front against the finished wall surface. The screws 18 are threaded into the seats therefor, in lugs 15, and taken up as far as conditions permit. The panelboard or fuse block may then, if necessary, be moved distantly along the studs to permit inserting and taking up of screws 27, in seats 29, to complete the assembly.

It will be understood that the foregoing description relates with particularity to the example illustrated, but is to be understood merely as descriptive, and not in a limiting sense. Obvious changes may be made in the parts, their relation and combinations within the scope of the invention as defined more particularly by the appended claims.

I claim:

1. A box, a cover, a panel member supported by the box and detachably associated with the cover, and means for adjustably positioning the panel member responsively to movement of said cover.

2. A box, a cover removably associated with the box, a panel member supported by and within the box, and means relating the cover and panel member, for movement of the panel member responsively to movement of the cover.

3. A box, a cover therefor, a panel and means carried by the box and associated with the panel for permitting adjusting movement of the panel relative to the box and cover, and holding means coacting with the cover, for keeping the panel in adjusted position.

4. A box, a cover, a panel member, means supporting the panel member by and within the box and relating the panel for distance adjustment between the box and cover, and means for securing the panel to the cover, in adjusted distance relation to the box.

5. A box, a panel member supported by and removably associated with the box, an apertured cover, and means for supporting the panel member within the box and permitting panel-adjusting movement, by manipulation of the panel, through the cover aperture.

6. A box, a panel member, a front, means carried by the front and cooperating with

the panel member to form a closure for the box, means for securing the front to the panel member as an assembled unit, and means for permitting movement of the panel
5 member, distantly, relative to the box, irrespective of its securement to the front.

7. A box, a panel member, a box front, mean for securing the front to the panel in constant distance relation, and means for dist-
10 tantly adjusting the assembled front and panel from the front of the box.

8. A box, a panel member, means carried by the box for supporting the panel member in adjustable relation to the box, a front de-
15 tachably secured to the box and means for securing the panel member to the front, said means adapted upon such securement, to fix the position of the panel member with respect to the box.

20 9. A box, a panel member, a combined support and guide for the panel member carried by the box, means formed by the panel mem-
ber constituting a seat for slidably receiving the guide, and means engaging the face por-
25 tion of the panel member for fixing its position on said support.

10. Enclosed electrical apparatus includ-
ing a box, a panel member, a panel support
projecting from the rear wall of the box,
30 means on the panel member forming a seat
for said support and relating the panel mem-
ber for distance movement along the sup-
port, a box front, and means including the
front for distantly positioning the panel
35 member within the box.
